By his Attorney, F. W. Barker.

UNITED STATES PATENT OFFICE.

WILLIAM SCOTT, JR., OF NYACK, NEW YORK.

COMBINATION-TOOL.

No. 803,512.

Specification of Letters Patent.

Patented Oct. 31, 1905.

Application filed May 2, 1904. Serial No. 205,889.

To all whom it may concern:

Be it known that I, WILLIAM SCOTT, Jr., a citizen of the United States of America, and a resident of Nyack, in the county of Rockland and State of New York, have invented certain new and useful Improvements in Combination-Tools, of which the following is a specification.

This invention relates to improvements in combination-tools; and it consists in the main of a pair of pivotal members having oppositely-bowed outer ends forming jaws and containing removable wrench-blocks, said jaws and blocks exercising a double gripping function.

In the drawings accompanying this application, Figure 1 is a side view of my improved tool, and Fig. 2 is a front view thereof.

In the formation of my improved combined tool I provide a two-part pivotal device, the handle portions of which may comprise parts of other tools, while the head portions thereof may constitute and include further tools.

25 In describing said parts let A indicate a hammer member bearing the hammer-head *a*, and B the other hammer member bearing the claws *b*. Said members A and B are crossed and pivotally united by a pivot, as C.

30 The handle portion of member A is provided with an offset extension A' in the form of a jaw of a pair of wire-cutters, the other jaw whereof, as D, being pivotally united thereto by pivot *d* and extending rearwardly into a handle D'. Similarly, the handle portion of member B is provided with an offset extension B' in the form of a jaw of a pair of pliers, the other jaw whereof, as E, being pivotally united thereto by pivot *e* and extending rearwardly into a handle E'.

35 As will be noted, the bipart hammer-head is composed of the oppositely-bowed jaws *a' b'* of members A B, respectively, the meeting edges thereof being inwardly beveled. Set 40 within the jaws *a' b'*, respectively, are the oppositely-disposed crescent-shaped wrench-blocks F F', which unitedly form a pipe-wrench. Said blocks F F' may be connected to the jaws *a' b'* by means of integral shanks, as *f*, which fit within slots prepared therefor

in said jaws (indicated by dotted lines in Fig. 1) and are secured by rivets or the like, as *f' f''*.

A space, as G, exists between the outer surface of the pipe-wrench and the inner surface of the jaws *a' b'*.

The various uses to which the above-noted tools and implements may be put will be readily comprehended.

By means of the jaws *a' b'* and gripper-blocks F F' a two-fold hold or purchase may be had upon an article held thereby, this being an important function of my improved device. It is evident that when gripping a bar of metal with a single pair of jaws it is sometimes difficult to obtain a rigid hold thereof, whereas if such bar be gripped at two different points it may be more securely held. This latter is the result I attain by means of the double grip afforded through the joint-grippers *a' b'* and F F'.

When desired to remove a horseshoe from the hoof, the beveled jaws *a' b'* are caused to meet beneath the shoe, whose outer surface bears against the outer surface of the wrench-blocks F F', whereby a good purchase is obtained in wrenching or tearing the shoe from the hoof.

While the means of handling the remaining tools is too obvious to need explanation, attention is directed to the particular contour of the handles D' and E' of the wire-cutter and pliers, respectively, said contour when these implements are closed forming a very convenient hand-grip for the hammer, whereby this latter tool may be wielded with efficiency.

The members A and B are separated to form a space H, within which certain articles may be grasped when of too great a bulk to be gripped between the jaws *a' b'* and blocks F F'.

When the wrench-blocks F F' become worn with usage, they may be removed and new ones inserted in their place, as is obvious.

Having now described my invention, I declare that what I claim is—

In a tool of the class described, a pair of pivoted handle members provided at their outer ends with oppositely-bowed and in-

wardly-beveled gripping-jaws, said jaws when closed forming a substantially circular opening in which is mounted a pair of crescent-shaped wrench-blocks, said blocks being removably secured to the bowed portions of the jaws by means of shanks passing through slots at the rear of the bowed portions; the forward edges of the crescent-shaped blocks contacting when the jaws are closed whereby

a double gripping function can be exercised between the blocks and the jaws.

Signed at New York city this 16th day of April, 1904.

WILLIAM SCOTT, JR.
